UNITED STATES PATENT OFFICE.

LESTER A. WERNERY, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING-MACHINE.

1,347,197.

Specification of Letters Patent.

Patented July 20, 1920.

Application filed January 5, 1917. Serial No. 140,818.

To all whom it may concern:

Be it known that I, LESTER A. WERNERY, a citizen of the United States, residing in Brooklyn borough, in the county of Kings, 5 city and State of New York, have invented certain new and useful Improvements in Typewriting-Machines, of which the following is a specification.

My invention relates to typewriting machines and more particularly to tabulating devices for such machines. It is herein disclosed as applied to a combined column-selecting and decimal tabulating device, forming part of an Underwood typewriting machine. In such column-selecting and decimal tabulating devices, it is advantageous to have a decimal tabulating device which will be effective even if no column-selecting key is depressed, and yet to provide connections such that if a column-selecting key is depressed, the decimal tabulating mechanism will bring the carriage to rest by the depression of a single other key. It is also an advantage to many people to be able to 20 set the column-selecting key and then later depress the decimal tabulating key. It is also desirable to have a mechanism for column-selecting which can be easily incorporated with the standard types of machine 25 manufactured on the large scale, thus reducing to a minimum the necessary special work in producing a special machine adapted to special needs. Besides this, it is advantageous to have the connections in the 30 machine such, that if the keys are depressed in the wrong order, the operative can correct the position of the carriage by a second operation of the keys in proper order without having the attention distracted by having to push back the carriage and reposition it, etc.

It is further advantageous to have the settable parts, such as the tabulating stops, either convenient to the front of the machine 45 themselves or to have them settable by some ordinary mechanism which is at the front of the machine.

With these and other advantages in mind, I have found it possible to utilize one of the 50 ordinary forms of tabulating mechanism such as the ordinary key-set decimal tabulating mechanism of the Underwood typewriting machine and to combine therewith a column-selecting rack bar adjacent to the 55 front of the machine with keys therefor, for selecting columns, adjacent to and above the

keyboard, said latter keys being adapted to be held in place when depressed until the carriage substantially reaches its position to be arrested and then the carriage may release the key practically in the act of being brought to rest. The key itself while depressed, being numbered on the front, serves as an indicator to indicate at what column the machine has been set to come to rest. 60 65

Other features and advantages will hereinafter appear.

In the accompanying drawings,

Figure 1 is a skeleton perspective view showing an Underwood typewriting machine having my invention applied thereto. 70

Fig. 2 is a schematic view of my invention showing the carriage and a few coöperating parts.

Fig. 3 is a sectional side view of the machine seen in Fig. 1, the parts being in normal position. 75

Fig. 4 is a view similar to Fig. 3, but showing the position of parts the instant before the column-selecting mechanism is released to arrest the carriage at the second column. 80

In the usual Underwood typewriting machine, type-keys 1, depress key levers 2 to swing type-bars 3, by means of sub-levers 4, 85 upwardly and rearwardly against the usual revoluble platen 5, so that types 6 and 7 will print against the front side of said platen. As each type-bar approaches the platen, a heel 8 thereon strikes a universal bar 9, moving it rearwardly to vibrate the usual detent and feeding dogs 10 and 11. These dogs form part of the escapement mechanism and coöperate with the escapement wheel 12, to permit the typewriter carriage including the 90 platen to be drawn along by the spring barrel 13, a step at a time; the escapement wheel 12, for this purpose being connected to a pinion 14, which meshes with a rack bar 15, the latter connected to the typewriter carriage 16. The carriage runs on rails 17 and 18, in the frame of the machine. 95

In order to enable the carriage to be rapidly positioned at any desired point, a decimal tabulating key 19, on the front 105 end of a key lever 20, may be depressed to raise or project a plunger 21, at the rear of the machine into the path of a carriage stop 22 on a rack bar 23. Any stop 22, which is able to be effective projects some distance 110 below the rack bar 23, and when in that position, strikes against any fully elevated

plunger or counter stop 21, thus arresting the carriage. For the purpose of releasing the carriage from the escapement mechanism to bring it automatically and rapidly 5 to the position where it may be arrested by the projected stop 21, the rack bar 15 is adapted to be lifted out of engagement with the pinion 14. To thus lift it, each plunger or counter stop 21 is provided with a heel 10 24, which underlies a short universal bar 25, pivoted at 26. Whenever any plunger stop 21 is raised, it rocks the universal bar 25, swinging down a rock arm 27, causing said arm to draw down on a link 28, which is pivoted to a short lever 29, said lever having at 15 its front end an idle roll 30, which rides on a smooth part 31, of the rack bar 15. The connections are such that the rising of the plunger stop draws down the link 28, 20 lifting the roll 30, and thereby lifts the rack bar 15 clear of the pinion 14, with the result that the spring barrel 13 will draw the carriage along until the carriage is arrested by some fully projected stop 21, when that 25 stop intercepts the downwardly projecting stop 22 on the typewriter carriage.

In the machine herein disclosed, the stops 22 are of the key-settable type, and for this purpose, there is provided at the front 30 of the machine a stop setting key 32, which is adapted to draw down a stop setting lug 33, which overlies the settable stops 22, and is of such width and so positioned, that when the key 32 is depressed, the lug 33 35 will depress one and only one of the stops 22 from the normal position seen in full lines in Fig. 3 into the position seen for the farther stop in said figure. To thus draw down the setting lug 33, said lug is 40 formed at the upper end of a link 34, extending to the bottom of the machine, where it is pivoted to a rock arm 35, fast on a rock shaft 36. Also fast on said rock shaft is a second rock arm 37, connected by a link 45 38 to the lever 39, of the stop setting key 32. The connections are such, that the depression of the key draws down the lug 33, against the tension of its spring 40, thereby setting a stop. The relationship 50 of parts is such, that if the typewriter carriage is positioned according to its scale 41, at any given point, the stop 22 depressed with the carriage so positioned, is the stop which will arrest the typewriter carriage at 55 that point if the decimal (i. e., period) decimal-tabulating key 19 is depressed. The stops 22 may be returned from their set position to their normal position by actuating an ordinary stop resetting bar 42, provided with slanting cam slots 43 engaging pins 44 to enable the sliding of the resetting bar 42 to lift the stop 22 upwardly. Within 60 the rack bar 23 are staggered detents 45, co-operating with detent notches 46 in their various stops. The parts so far described

are broadly old, but as will appear later are especially adjusted or modified, so that their operation will enable new functions to be obtained from certain of them for the purpose of coöperating with other parts 70 hereinafter described.

To enable the carriage to be arrested in any one of several zones, there are provided column-selecting keys 47, which are adapted to coöperate with column stops or selectors 75 48, the latter being adjusted along a rack bar 49, at the front of the machine. The rack bar 49 is suitably graduated to correspond with the scale bar 41, and is provided with notches 50, at letter-space intervals on opposite sides of the bar, so that the stops 48 when inserted, straddle the bar and engage the bar into both of their legs. The rack bar 49 is fast to brackets 51, which in turn are fast to the front of the frame 80 52 of the typewriter carriage. The brackets 51 extend over the scale plate 41 of the typewriter, thus bringing the rack bar 49 to a point where it is convenient to set the stops, and they are far enough below the 85 surface of said scale to enable the scale numerals to be easily read, and in addition are so positioned as to enable the ordinary margin stops to be easily accessible to the fingers of the operator.

In order to enable the column stop keys 47, to select columns for the purpose of arresting the carriage, each key is mounted on the front and lower end of a key lever 53, these keys being arranged in a substantially horizontal line with the key faces vertical, to enable them to be easily read. The key-levers, except the central one which is substantially straight, are bent in toward the center of the machine, so that the terminal extensions 54 of said key levers which coöperate with the stops 48 are in a single vertical line.

The column key levers 53, are journaled on a transverse rod 55, which is rigid with 110 and forms part of a decimal key controlling frame 56, said frame also including the vertical links 57, and a horizontal bar 58, which normally lies just out of range of the decimal key levers 20, when said key-levers 115 are depressed. The depression of a column-selecting key 47 lifts the rod 55 together with the frame of which it forms a part, thus raising the decimal key controlling rod 58 almost, but not quite, into contact with the decimal tabulating key-levers 20. To do this, each column-selecting key-lever 53 is provided with a cam 59, which the depression of the key carries against a fixed rigid horizontal rod 60, fast in the frame of 120 the typewriting machine. A continued depression of the key causes the cam 59 to raise the key lever, and therewith the frame until a latch or hook extension 61 of the cam 59 engages the rod 60 and acts as a de- 130

tent, thus locking said key in its depressed position, thereby holding the decimal key controlling rod 58 in its elevated position. If any decimal tabulating key 19 is then depressed, it will go down far enough to operate the short universal bar 25 and release the escapement rack bar 15, as seen in Fig. 4, but cannot go down far enough to raise its plunger 21 into the path of any depressed rack stop 22. In other words, the decimal tabulating key will release the carriage and allow the carriage to be drawn along, but it is unable to arrest the carriage. Means are provided, however, whereby the decimal tabulating key can descend and raise its counter stop 21, to arrest the carriage. For this purpose, the column stops 48, at the front of the machine, are each provided with a trip or cam lug 62, the lug on each stop being at a different height from the lug on any other stop, so that the lugs may have a selective action. As the typewriter carriage travels along, when released as above described, one of the lugs 62 will lie in the path of a cam extension 63, on the terminal extension 54, of the depressed column-selecting key 47, with the result that when said lug strikes said cam, it will cam the terminal extension 54 rearwardly, thus freeing the key 47 from the rod 60 and allowing the frame 57 to drop carrying with it the decimal key control bar 58. This takes place about two letter-spaces before the stop 22 comes to the partly elevated plunger (see Fig. 2 in which only the set decimal column-stops are shown), and allows the depressed decimal key 19 which has released the carriage to go down farther under the pressure of the operative's finger, thus raising the counter stop 21 at the rear end thereof into the path of the stop 22, thereby arresting the carriage at the desired point.

The rising of the decimal tabulating key 19, under the influence of its spring 64, when it is released, allows the rack bar 15 to mesh with the pinion 14, thus putting the carriage of the typewriter again under the control of the escapement wheel 12. In order to make the terminal extensions of the column-selecting keys 47 coöperate with the proper lugs 62, the cams 63 are normally somewhat out of alinement with the lugs 62 with which they are to coöperate (see Fig. 3) and the raising of the frame 57 brings them into alinement (see Fig. 4).

In order to steady the lower part of the frame 57, it is connected by idle links 65 to the frame of the machine, and the upper end thereof is guided in slotted brackets 66 in the slots of which ride extensions 55^a of the rod 55. In order to assist the return of the column-selecting keys 47 and to hold them normally ineffective, each is provided

with a light flat spring 67, which bears 65 against the rod 60. The frame 57 may be held in its downward normal position by means of a light spring 68, which serves to take up any looseness and thus prevents rattling.

In order to keep the terminal extensions 54 of the column-selecting key levers 53, out of the way of catching on the clothing of the operative or on papers, etc., said extensions rise behind the rack bar 49 and the stops 48 are so positioned that the lugs 62 that co-operate therewith are also placed on the rear side of the rack bar.

Variations may be resorted to within the scope of the invention, and portions of the 80 improvements may be used without others.

Having thus described my invention, I claim:

1. In a typewriting machine, the combination with a traveling carriage, of a tabulating key adapted to release the carriage and arrest the carriage, a second tabulating key adapted to make said first tabulating key ineffective to arrest the carriage, and carriage-controlled means for again making 90 said first key effective to control the carriage.

2. In a typewriting machine, the combination with a traveling carriage, of a rack bar thereon carrying tabulating stops, key-operated stops adapted to coöperate with said first-named stops to arrest the carriage, cams settable on said carriage for selectively determining when said key-operated stops may be effective, and column-selecting keys for 100 selectively making said cams effective.

3. In a typewriting machine, the combination with a traveling carriage, of a plurality of decimal tabulating keys, a bail universal to said keys for making them inoperable to arrest the carriage, cams for selectively controlling said bail at various points in the travel of said carriage, and keys for selectively determining which of said cams shall control said bail.

4. In a typewriting machine, the combination with a traveling carriage, of a plurality of decimal tabulating keys, a bail universal to said keys for making them inoperable to arrest the carriage, separately settable cams 115 for selectively controlling said bail at various points in the travel of said carriage, and keys for selectively determining which of said cams shall control said bail.

5. In a typewriting machine, the combination with a traveling carriage and stops for arresting the carriage, of key-controlled counter-stops, carriage-operated cams for determining when said counter-stops may be effective, and devices settable to selectively 125 make said cams effective.

6. In a typewriting machine, the combination with decimal tabulating keys and a

traveling carriage controlled thereby, of a bail for controlling said keys, and column-selecting keys for selectively controlling said bail at various points in the travel of the 5 typewriter carriage.

7. In a typewriting machine, the combination with a traveling carriage and stops settable at the rear thereof, of a key at the front of the machine for selectively setting said 10 stops, coöperating column-stops, and normally ineffective cams settable at the front of said carriage for controlling the effectiveness of said column-stops.

8. In a typewriting machine, the combination with a traveling carriage and stops settable at the rear thereof, of a key at the front of the machine for selectively setting said 15 stops, coöperating column-stops, normally ineffective cams settable at the front of said 20 carriage for controlling the effectiveness of said column-stops, and column-selecting keys for selectively controlling said cams.

9. In a typewriting machine, the combination with a traveling carriage and a tappet 25 thereon, of a key-controlled cam adapted to be operated by said tappet when moved to effective position by its key, a bail for holding said key in effective position, and a spring forming part of said key and bearing 30 against said bail tending to return said key to normal position.

10. In a typewriting machine, the combination with decimal tabulating keys adapted to release the carriage and arrest it, of a 35 second tabulating key adapted to make the first-named keys ineffective to arrest the carriage, and a cam settable by said last-named key for causing the carriage to make said 40 first-named keys effective to control the carriage.

11. In a typewriting machine, the combination with a traveling carriage and a tabulating device for releasing the carriage and arresting it, of a series of selectively operable 45 cams separately settable for controlling the operation of said tabulating device, but normally ineffective thereon, and a key for each cam for making it effective.

12. In a typewriting machine, the combination with a traveling carriage, of decimal 50 tabulating keys, column-selecting keys, means whereby the decimal tabulating keys are effective to arrest the carriage at the next column, if no column-selecting key has been 55 depressed, and connections whereby the depression of a column-selecting key after the carriage has been already passed by the column selected by that key, makes the decimal tabulating keys ineffective.

60 13. In a typewriting machine having a front scale and a traveling carriage, the combination with an extension of said carriage extending in front of said scale, of a rack bar forming part of said extension, stops

having variably elevated rearward extensions 65 extending from said rack bar, and column-selecting key-levers rising behind said rack bar to coöperate with said extensions.

14. The combination with a typewriter carriage and column-stops therefor, of normally ineffective counter-stops, keys for 70 making the counter-stops effective, a plurality of devices settable to hold the counter-stops ineffective to arrest the carriage, means for releasing the carriage at the operation of 75 said keys, and means for selectively operating said devices by travel of the carriage, to permit the counter-stops to become effective.

15. In a typewriting machine, the combination with a traveling carriage and a 80 rack bar thereon, of stops settable on said rack bar, decimal counter-stops adapted to move to arrest the carriage by said rack stops, connections whereby said counter-stops cause said carriage to feed free of any 85 escapement mechanism on the first operation of a counter-stop before it comes into effective position to arrest the carriage, column-selecting keys for varying the column in which said counter-stops may be effective 90 to arrest the carriage, decimal tabulating keys operating said counter-stops, a bail universal to said last-named keys for locking them, and means under the control of said column-selecting keys for making the 95 bail effective.

16. In a typewriting machine, the combination with a traveling carriage and a rack bar thereon, of stops settable on said rack bar, decimal counter-stops adapted to 100 move to arrest the carriage by said rack stops, connections whereby said counter-stops cause said carriage to feed free of any escapement mechanism on the first operation of a counter-stop before it comes into 105 effective position to arrest the carriage, column-selecting keys for varying the column in which said counter-stops may be effective to arrest the carriage, decimal tabulating keys operating said counter-stops, a 110 normally ineffective bail for locking said decimal keys, means under the control of said column-selecting keys for making said bail effective, and means for releasing said bail by travel of the carriage.

115 17. In a typewriting machine, the combination with a traveling carriage, of column-selecting devices therefor including column-selecting keys, settable stops on said carriage, coöperating cams under the control of said selecting keys normally out of range of said stops, both vertically and horizontally, devices whereby the depression of a column-key moves its cam into effective position to be operated by travel 120 of the carriage, decimal selecting keys, a bail for controlling said decimal selecting keys and normally ineffective, and connections 125

whereby the setting of a cam makes said bail effective and the operation of a cam makes said bail ineffective.

18. In a typewriting machine, the combination with decimal tabulating keys, of a bail normally ineffective to prevent action thereof, a series of hooks for selectively controlling said bail, and carriage-lugs for making said hooks selectively ineffective.

19. In a typewriting machine, the combination with a traveling carriage, of decimal selecting keys, a bail for making said keys ineffective, and a carriage-controlled hook for making said bail ineffective.

20. In a typewriting machine, the combination with a traveling carriage and normally manually-operable decimal-tabulating stops therefor, of separately settable column-stops for determining in what decimal column the decimal stops may be effective, a device for making the decimal stops inoperable, and carriage-operated column-selecting devices selectively effective on the device to cause decimal stops to be operable.

21. In a typewriting machine, the combination with a traveling carriage, of means normally holding the carriage at rest, a series of normally ineffective column-selecting cams adapted to be moved by the carriage when effective, a series of keys each adapted to make its cam effective and ineffective on any other cam, a tabulating device for arresting the carriage at the point determined by the effective cam, and keys controlling said tabulating device, adapted to make said holding means ineffective.

22. The combination with a traveling carriage and column-stops therefor, of normally ineffective counter-stops, keys for making the counter-stops effective, a normally ineffective bail adapted to hold the

counter-stops ineffective to arrest the carriage, a plurality of devices separately settable to make the bail effective, members selectively settable along the travel of the carriage to selectively unset said devices to permit the counter-stops to become effective, and means for releasing the carriage at the operation of said keys.

23. In a typewriting machine, the combination with normally operable keys, of a normally ineffective bail for locking them, a series of column-keys for setting said bail to locking position, and means for selectively unsetting said bail by travel of the carriage, according to the column-key operated.

24. In a typewriting machine, the combination with a traveling carriage and a series of stops for arresting it, of a series of devices including latches, a series of keys for setting said devices to be held by their latches, and a series of trips such that one or another of them will be effective on any set device to select the column in which a stop may be effective.

25. In a typewriting machine, the combination with a traveling carriage and stops for arresting the carriage, of a series of normally ineffective devices including latches adapted to be set to hold the devices effective, tabulating stops normally operable but adapted to be made inoperable by any set latch, and releasing devices operated by the carriage and selectively settable for releasing said latches to enable the tabulating stops to be operated to arrest the carriage.

LESTER A. WERNERY.
